UNITED STATES PATENT OFFICE

MILTON S. LAKE, OF DALLAS, TEXAS

SPEED BOAT

Application filed June 26, 1930. Serial No. 464,071.

This invention relates to new and useful improvements in anti-friction attachments for speed boats.

One object of the invention is to provide friction eliminating means for the second step of a speed boat whereby less resistance will be offered to the forward movement of the boat when the latter is riding on its second step at high speed.

10 A particular object of the invention is to provide transverse rollers, each extending substantially the entire width of the bottom of the boat and spaced in such close relation as to provide substantially no space 15 therebetween, except for clearance whereby the entire surface presented to the water will revolve.

Another object of the invention is to arrange the forward rollers on the second step 20 so as to project below the heel of the first step so as to take the forward thrust or impact and thus accelerate the rate of speed at which the boat moves through the water.

A construction designed to carry out the invention will be hereinafter described together with other features of the invention.

The invention will be more readily understood from a reading of the following specification and by reference to the accompanying drawings in which an example of the invention is shown, and wherein:

Figure 1 is a side elevation of a speed boat having mounted thereon an attachment constructed in accordance with the invention.

35 Figure 2 is a perspective view showing the mounting of the rollers on the boat.

Figure 3 is a transverse vertical sectional view taken on line 3—3 of Figure 1.

40 Figure 4 is a partial longitudinal sectional view taken on line 4—4 of Figure 3.

Figure 5 is a view similar to Figure 4, showing a modified form of roller mounting, and

45 Figure 6 is a detailed sectional view of the roller mounting.

In the drawings the numeral 10 designates a speed boat of the type having a two step bottom 11 with a first step 12 and a second step 13. A plurality of rollers 14 are disposed transversely of the entire width

of the bottom of the second step, as best shown in Figure 2. As shown in Figure 6 the ends 15 of each roller are reduced and are journaled in ball-bearings 16 of bearing hangers 17 which are secured to and depend from the sides of the boat.

55 The forward roller 14' is positioned directly behind a heel 18 which is formed between the end of the first step and the beginning of the second step. This roller 14' is mounted so as to extend below the heel 18 whereby as the first step rises out of the water due to the increasing speed of the boat in the water, the lower portion of the roller and the successive rollers will contact with 60 the surface of the waters and roll thereon.

65 The rollers are mounted in close relation with substantially no space therebetween except for clearance so that the entire surface presented to the water at a high rate of speed of the boat will revolve. In this manner less resistance is offered to the forward movement of the boat when the latter is riding on its second step and the rate of 70 speed at which the boat moves through the water is accelerated.

75 It is pointed out that as the boat increases its speed the water will become more solid and with the rollers taking the forward thrust or impact, they will ride upon the water and so lessen to a great extent the drag of the boat.

80 In Figure 5 I have shown a modified form 85 of roller mounting in which the bottom 19 of the boat is corrugated to conform to the rollers so as to provide substantially no space therebetween except for clearance.

85 Various changes in the size and shape of the different parts, as well as modifications and alterations, may be made within the 90 scope of the appended claims.

What I claim, is:

1. A boat hull including a bottom surface comprising a relatively smooth forward portion adapted to make sliding contact with the water under the boat when the boat is propelled relatively slowly, and a second portion to the rear of the first portion including a plurality of freely rotatable transverse rollers mounted in tandem arrangement 95 100 105

adapted to make rolling contact with the water.

6 2. A boat hull as claimed in claim 1, in which the second portion extends over all of the area of the bottom which is adapted to contact with the water when the boat is propelled at relatively high speed.

10 3. A boat hull including a two step bottom surface, the forward step being relatively smooth and adapted to make sliding contact with the water, and a plurality of freely rotatable transverse rollers mounted in tandem arrangement on the rear step and adapted to make rolling contact with the water, the forward roller being positioned 15 immediately behind the heel of the forward step and depending slightly below the level of the forward step.

In testimony whereof, I affix my signature.
